UNITED STATES PATENT OFFICE.

ROY B. MESSENGER, OF POMEROY, WASHINGTON.

GAME.

1,165,798.

Specification of Letters Patent. Patented Dec. 28, 1915.

Application filed July 10, 1915. Serial No. 39,978.

To all whom it may concern:

Be it known that I, ROY B. MESSENGER, a citizen of the United States, residing at Pomeroy, in the county of Garfield and State of Washington, have invented certain new and useful Improvements in Games, of which the following is a specification, reference being had to the accompanying drawings.

10 My present invention relates to new and useful improvements in games and has particular reference to an improved game of the type embodying a playing board or field, and a spinning block, wherein the playing 15 pawn is initially placed and from which it is subsequently discharged on to the playing field, through the rotation or spinning of the spinning block.

One of the principal objects of the invention is to provide a game of the character 20 above stated, which is designed in such manner as to make it capable of use in playing a large and varied number of games.

The above, and other incidental objects of 25 a similar nature, which will be hereinafter more specifically treated, are accomplished by such means as are illustrated in the accompanying drawings, described in the following specification, and then more particularly pointed out in the claim which is appended hereto and forms part of this application.

With reference to the drawings, wherein there has been illustrated the preferred embodiment of this invention as it is reduced 35 to practice, and throughout the several views of which similar reference numerals designate corresponding parts, Figure 1 is a plan view; Fig. 2 is a section taken diametrically 40 through the playing board, on the line 2-2, of Fig. 1; Fig. 3 is a detail perspective view of the spinning block.

As disclosed in Fig. 1, the apparatus for 45 playing the present game includes broadly a playing board A, and a spinning block or top B. The playing board A is preferably formed from a solid block of wood of rectangular shape. While wood is preferably employed, it is obvious that a composition 50 or equivalent material may be substituted therefor, without departing in any way from the spirit of the present invention. The playing field is defined by an outer circle 10 which is described from the center of the 55 playing board and is of a diameter slightly less than the width of the board A. A

second or inner circle, concentric to the outer circle, is marked upon the playing field, as indicated at 11. Each of these circles may be painted or otherwise indicated upon the 60 playing field.

The annual space defined by these two circles is divided into a number of compartments or stalls, which as shown in Fig. 1, are preferably thirty-six (36) in number, 65 although a greater or less number of stalls may obviously be provided, if desired. The different stalls are defined by the radial partitions disclosed in Fig. 1. These partitions may be formed of sheet metal, to produce 70 the outwardly diverging walls or portions indicated at 12 and 13, in Fig. 1 or may be formed from wedge-shaped blocks of wood, rubberoid or any suitable composition. It is 75 now to be observed that the upper face of the block A is chamfered so that its central portion partakes of the nature of a cone, on the apex of which is seated the top B. Thus the central portion of the playing field inclines in all directions, toward the annular series 80 of stalls or compartments, so that when the marble or other pawn is released from the top, it will slide by gravity down the conical portion and into one of the stalls. The partitions which define the stalls are of such 85 height that their upper edges lie flush with the upper face of the marginal portion of the block A.

The spinning block or top heretofore designated by the numeral B, is preferably 90 formed from a solid block of wood, which is journaled upon a vertical central axle 15, which member rises from the apex of the conical portion of the playing field. The upper face of the top or block B is provided 95 with a segmental groove 16, which is provided with indentations or shallow recesses 17, and the upper end of which leads into a serpentine passage or bore 18, which is 100 formed in the top. The lower end of this serpentine bore opens through the side of the top and at the lower terminal thereof, as in Fig. 2.

It will now be readily apparent, particularly upon reference to Fig. 1, that a marble, ball bearing or equivalent pawn may be placed within the recess 17, so that it will normally be held against movement through the groove 16. If the top is spun in the well known manner, the pawn will be dislodged by centrifugal action and also caused 105 to move through the groove 16. The pawn 110

- will then pass down through the bore 18 and exit from the lower end of the top on to the conical portion of the playing field at the apex thereof. In order that the pawn may 5 not freely enter the different stalls, each stall is guarded by a pin 19. These pins 19 are arranged in an annular series and are circumferentially spaced so that one pin is disposed in front of each stall.
- 10 A finger piece indicated at 20 is provided for the upper end of the top so that this member may be easily spun. In order that the top may freely rotate, it has been found desirable in practice, to interpose an annular 15 series of ball bearings between the bottom of the top and the central portion of the block A, as indicated at 21.
- 15 The actual construction and arrangement of the several parts of the game apparatus 20 being thus disclosed, it now remains to describe the manner in which the games are played and the rules governing the use of the apparatus. One game which may be 25 played with the present board, is that which may appropriately be called "Presidents." In this game the numeral accompanying each stall with the exception of those numbered 2, 6, 8, 10, 13 and 20, represent a President of the United States. If the spinner is 30 able, within a given range of time, to name the year in which the President took office, he scores the number of points equal to the product of the number accompanying the stall in which the pawn has lodged, by four. 35 If the spinner can accurately state the number of years the President was in office he may also add to his score the product of the number of the stall and five. The stalls 6 and 8 are blanks, which mean that the player 40 gains nothing when his pawn lodges in either one of them. Stalls 2 and 13 represent a fine, where the player must subtract from his score "2x13" or "2x2," as the case may be. Stalls 10 and 20 are rewards, for 45 the player whose pawn lodges in either one of them may add to his score, the product of

the numeral 10 or 20, as the case may be, by four. One thousand points may constitute the game, although any other appropriate number may be adapted. Obviously, the 50 above rules are subject to many modifications for the factors by which the penalty and reward stalls are multiplied, may be changed at will.

In reduction to practice, it has been found 55 that the form of this invention illustrated in the drawings and referred to in the above description as the preferred embodiment, is the most efficient and practical; yet realizing the conditions concurrent with the adoption 60 of this device will necessarily vary, it is desirable to emphasize the fact that various minor changes in the details of construction, proportion and arrangement of parts may be resorted to, when required, without sacrificing 65 any of the advantages of this invention, as defined by the appended claim.

What is claimed, is:—

A game board including a block having 70 an annular series of stalls opening toward the center of the block, a spinning top rotatably mounted upon the center of the block, a pin centrally arranged before the entrance of each stall, the surface of the block between the top and the pins being 75 free and unobstructed, said top having a segmental groove in its upper face provided with shallow recesses, said top being further provided with a serpentine bore, opening at its upper end into the groove, whereby a 80 pawn may be placed in the groove and upon rotation of the top be discharged through the bore and out the lower end of the top on to the playing board, whereon it may roll into one of the stalls. 85

In testimony whereof I hereunto affix my signature in the presence of two witnesses.

ROY B. MESSENGER.
